US0D1033862S

(12) **United States Design Patent** (10) Patent No.: **US D1,033,862 S**
(45) Date of Patent: ** Jul. 9, 2024

(54) **FOOTWEAR**

(71) Applicant: **Mountain Origins Design LLC**,
Jackson, WY (US)

(72) Inventors: **Kurtis Tamotsu Sakai**, Santa Barbara,
CA (US); **Stephen Sullivan**, Wilson,
WY (US); **Kelly Hill Shuptrine**,
Jackson, WY (US)

(73) Assignee: **Mountain Origins Design LLC**,
Jackson, WY (US)

(**) Term: **15 Years**

(21) Appl. No.: **29/831,911**

(22) Filed: **Mar. 23, 2022**

(51) LOC (14) Cl. **02-04**

(52) U.S. Cl.

USPC **D2/972**

(58) **Field of Classification Search**

USPC D2/896, 900, 902, 906-912, 916-924,
D2/969-979

(57) **CLAIM**

The ornamental design for footwear, as shown and described.

DESCRIPTION

FIG. 1 is a perspective view of a footwear.

FIG. 2 is a front view of the footwear in FIG. 1.

FIG. 3 is a rear view of the footwear in FIG. 1.

FIG. 4 is a left side view of the footwear in FIG. 1.

FIG. 5 is a right side view of the footwear in FIG. 1.

FIG. 6 is a top view of the footwear in FIG. 1; and,

FIG. 7 is a bottom view of the footwear in FIG. 1.

The broken lines show portions of the footwear that form no part of the claimed design.

1 Claim, 7 Drawing Sheets

US D1,033,862 S
